(57) **CLAIM**

We claim the ornamental design for a twistable remote control, as shown and described.

DESCRIPTION

FIG. 1 is a top isometric view of a first embodiment of a twistable remote control showing our new design;

FIG. 2 is a top plan view thereof;

FIG. 3 is a bottom plan view thereof;

FIG. 4 is a front elevation view thereof;

FIG. 5 is a top isometric view thereof in an expanded orientation;

FIG. 6 is a top plan view thereof in an expanded orientation;

FIG. 7 is a front elevation view thereof in an expanded orientation;

FIG. 8 is a top isometric view of a second embodiment of a twistable remote control showing our new design;

FIG. 9 is a top plan view thereof;

FIG. 10 is a bottom plan view thereof;

FIG. 11 is a front elevation view thereof;

FIG. 12 is a top isometric view thereof in an expanded orientation;

FIG. 13 is a top plan view thereof in an expanded orientation; and,

FIG. 14 is a front elevation view thereof in an expanded orientation.

In the drawings, the broken-line showing of buttons depicts environmental subject matter only and forms no part of the claimed design.
